United States Patent Office

Des. 215,964

Patented Nov. 11, 1969

215,964

SPOON OR SIMILAR ARTICLE

Ellen B. Manderfield, Syracuse, N.Y., assignor to Oneida
Ltd., Oneida, N.Y., a corporation of New York

Filed Mar. 19, 1969, Ser. No. 16,329

Term of patent 14 years

Int. Cl. D7—03

U.S. Cl. D54—12

FIG. 1 is a front view of a spoon showing my new design;

FIG. 2 is a rear view thereof;

FIG. 3 is a side view thereof, the undisclosed side being substantially identical with the side shown in FIG. 3;

FIG. 4 is an enlarged cross-section taken on line 4—4 of FIG. 1;

FIG. 5 is an enlarged cross-section taken on line 5—5 of FIG. 1;

FIG. 6 is an enlarged cross-section taken on line 6—6 of FIG. 1; and

FIG. 7 is an enlarged cross-section taken on line 7—7 of FIG. 1;

I claim:

The ornamental design for a spoon or similar article, substantially as shown and described.
